UNITED STATES PATENT OFFICE.

EDWARD F. RAYMOND, OF SANTA FE SPRINGS, CALIFORNIA.

COMBINATION ROLLER BIT AND DISK STRUCTURE.

Application filed July 6, 1925. Serial No. 41,654.

To all whom it may concern:

Be it known that I, EDWARD F. RAYMOND, a citizen of the United States, and resident of Santa Fe Springs, in the county of Los Angeles, State of California, have invented new and useful Improvements in a Combination Roller Bit and Disk Structure, of which this is a specification.

This invention relates to a rotary boring tool employing rotatable cutters, and pertains particularly to the means for lubricating the cutter bearings. In drilling wells, the cutting tool is disposed in the hole at a distance far from the surface. The supply of lubricant thereto from the surface is attended to with difficulty and necessitates additional parts.

It is desirable to have a supply of lubricant in the tool or at a place adjacent the cutters and to supply this lubricant as the tool cuts and is advanced in the hole. Rotary hydraulic boring tools have been provided which have lubricating systems wherein the feed means for lubricant is operated by pressure of the circulation liquid. In such cases, the feed of the lubricant begins when lowering of the tool is begun, and there is a wastage of lubricant. Furthermore, the time that the tool may be operated while it is cutting into the formation is substantially decreased. The primary object of this invention is to provide lubricating means of the character described which will not begin feeding lubricant until rotation of the tool is begun and which will continuously feed lubricant thereafter. Another object of this invention is to provide a tool having cutter surfaces and the wash so arranged as to clean the cutters by washing the cuttings lodged thereon outwardly. In addition to the broader objects of this invention, there are certain details of design whereby a strong, durable, efficient and positively operated structure is obtained.

These objects together with other objects and corresponding accomplishments are obtained by means of the embodiment of my invention illustrated in the accompanying drawing, in which:

Fig. 1 is an axial section through a roller bit; and Figs. 2, 3, 4, and 5 are sections as seen on lines correspondingly numbered in Fig. 1.

Referring more particularly to the drawing, 6 indicates the stock or body of the tool having at the upper end a box with a

threaded internal taper as indicated by 7. A chamber portion 8 for the wash liquid is closed from communication with a barrel 9 by means of a plug 10. The bore 9 extends close to the bottom of the tool, and the upper end thereof is in communication with the exterior through a passage 11. The body of the tool ends in a leg 12 at the center and offset outer legs 13. Extending through legs 13 and secured to leg 12 are shafts or pintles 14. A shaft 14 has rotatably mounted thereon a pair of roller cutters 15 and 16. Each shaft has an oil duct opening to the surface thereof upon which the rollers are mounted and communicating with passages 17 which branch from a central passage 18 communicating with the bore 9. A chain or other flexible member 19 is secured to a plug 10, the other end of the chain being secured to a piston 20 which floats in the bore. It is obvious that, if the port 18 is open, chamber 9, filled with lubricant, and the piston in the position shown, circulation fluid on its return will enter the passage 11 and act upon the top of piston 20 forcing the latter and lubricant downwardly through the port 18 and to the bearing surfaces of the shafts. This would occur immediately upon placing the tool in the hole and starting circulation, circulation commonly being maintained while the tool is being lowered. As it is not desirable to start lubrication until the tool is started in operation to cut, means is provided to close the port until rotation is started.

This means comprises a gate 21 slidably mounted in a way within the tool so that the gate may be projected across the port 18 to close the latter. Back of the gate is a spring 22 tending to force the gate outwardly. The gate has a rack upon one side thereof meshing with a pinion 23 journalled in the body, it in turn meshing with a pinion 24 mounted upon a roller 25. The roller is journalled in a recess in the side of the tool so that it projects beyond the periphery thereof a distance such that it will engage the sides of the hole, and by rotation of the roller a consequent rotation of the pinion will be caused. Rotation in a right hand direction will cause the gate 21 to be moved outwardly and eventually the pinion teeth will ride over the end of the teeth on the rack. Thereupon, the spring 22 forces the gate into its outermost position so that

it will not be operated by the pinion. A plug 26 closes the gate channel and provides access thereto for resetting the gate.

Water courses 27 extend downwardly through the body and divide at the lower end directing the wash liquid over the rollers 15 and 16. It will be noted that the rollers have bevelled edges with transverse corrugations and rounded outer side faces 19 with annular corrugations.

In the operation of the tool, plug 10 and piston 20 are removed and gate 21 closed. The barrel 9 is then filled with lubricant. Piston 20 is replaced and plug 15 10 inserted in position. The tool is now ready for operation. Lubricant cannot be discharged from the chamber unless gate 21 is opened. During the time that the tool is lowered in the hole, the gate is maintained 20 closed. Upon starting the tool rotating at the bottom of the hole, roller 25 engages the side wall of the hole and turns to retract gate 21. After the gate has been removed so that the teeth on the rack and pinion are out of mesh, spring 22 moves the gate into position such that it is disconnected from the pinion and roller 25. The pressure of the circulation fluid upon 30 the outside of the tool acts upon piston 20 and forces the latter downwardly in the barrel ejecting lubricant through port 18 and passages 17 feeding it to the pintle bearing surfaces.

What I claim is:

25 1. A hydraulic rotary boring tool comprising a body having rotatable cutters, there being an expandable lubricant chamber in said body and lubricant ducts leading therefrom to the bearings of the cutters, and lubricant control means for preventing the flow of lubricant from said chamber and operable by rotation of said tool to permit the flow of lubricant therefrom.

2. A hydraulic rotary boring tool comprising a body having rotatable cutters, there being an expandable lubricant chamber and lubricant ducts leading therefrom to the bearings, means for forcing lubricant from said chamber operable by pressure of the circulation liquid, valve means for preventing the flow of lubricant through

said ducts, and means operable by rotation of said tool to open said valve.

3. A rotary boring tool comprising a body having rotatable cutters, there being an expandable lubricant chamber in said body and lubricant ducts leading therefrom to the bearings of the cutters, lubricant control means for controlling the flow of lubricant from said chamber, and a roller disposed at the periphery of said body operable by the rotation of the tool to initiate flow of the lubricant.

4. A rotary boring tool comprising a body having rotatable cutters, there being an expandable lubricant chamber and lubricant ducts leading therefrom to the bearings of the cutters, means for forcing lubricant from said chamber operable by the pressure of the circulation liquid, valve means for preventing the flow of lubricant through said ducts, and a roller disposed at the periphery of said body operable by rotation of the tool to open said valve and initiate the flow of said lubricant.

75 5. A hydraulic rotary boring tool as specified in claim 2 characterized by said valve means comprising a slideable cage with a rack formed thereon, a pinion in mesh with said rack, and gearing connecting said pinion to said roller.

6. A hydraulic rotary boring tool comprising a body having rotatable cutters, there being a lubricant barrel in said body and lubricant ducts leading therefrom to the bearings of the cutters, a floating piston in said barrel, said barrel being in open communication with the circulation fluid space, valve means for preventing the flow of lubricant through said ducts, a roller disposed at the periphery of said body operable by the rotation of said tool to open said valve means and initiate the flow of the lubricant characterized by said valve means comprising a slideable gate with a rack formed thereon, a pinion in mesh with said rack, and gears connecting said pinion to said roller.

90 In witness that I claim the foregoing I have hereunto subscribed my name this 26th day of June, 1925.

EDWARD F. RAYMOND.
